UNITED STATES PATENT OFFICE.

WILLIAM W. WILSON, OF LOS ANGELES, CALIFORNIA.

UNDERREAMER.

1,078,568.

Specification of Letters Patent. Patented Nov. 11, 1913.

Application filed June 19, 1911. Serial No. 633,911.

To all whom it may concern:

Be it known that I, WILLIAM W. WILSON, a citizen of the United States, residing at Los Angeles, in the county of Los Angeles and State of California, have invented new and useful Improvements in Underreamers, of which the following is a specification.

This invention relates to under-reamers, such as are customarily employed for reaming well holes or borings beneath the casing, prior to lowering of the latter; and it has for its object to provide certain improved features novel with relation to assemblage, formation, construction, relative arrangement and combination, all of which will be superior in point of relative simplicity and inexpensiveness of construction and organization, positiveness of operation, efficiency in service, facility of control, and durability and length of life, and which will be generally superior in point of serviceability.

With the above and other objects in view, the invention consists in the novel provision, construction and organization, in parts and with respect to their total assemblage, all as hereinafter described, shown in the drawing, and finally pointed out in claims.

In the drawing:—Figure 1 is a side elevation, partly broken away, of an underreamer constructed and organized in accordance with the invention; Fig. 2 is a fragmentary side elevation of a portion of the same, taken at right angles to the line of vision in Fig. 1. Fig. 3 is an outer face view of a cutter or bit of which two are shown in Fig. 1, the same being in detached position; Fig. 4 is a section on the line 4—4, Fig. 1, looking in the direction of the appended arrows; and, Fig. 5 is a section on the line 5—5, Fig. 1, looking in the direction of the appended arrows.

Corresponding parts in all the figures are denoted by the same reference characters.

Referring with particularity to the drawing, A designates the body or stem of an underreamer constructed to embody the invention, the same being provided with cutters or bits a disposed adjacent to the lower end portion of the stem or body A, and with a projecting working member B depending from the lower end of the stem or body A and disposed at its upper end portion between the cutters or bits a. The bits are mounted to slide longitudinally of the stem into and out of positions of operative pro-

jection, and tension means C are provided for positively moving the same into positions of operative projection; said tension means being mounted upon or carried by the stem A.

In the form of construction and arrangement of parts selected for specific disclosure in the drawing, the stem or body A is provided at its lower end portion with an internal chamber 6 opening outwardly at opposed sides of the stem, as at 6^a, and at the bottom of the stem, said chamber 6 being closed at the top excepting for communication with opposed grooves or channels 7, 7^a at opposite faces of the stem, which channels 7 open upwardly through a diminished portion 7^b of the stem, and open downwardly into the lateral portions of the chamber 6, between dovetail guides 8 confining each lateral orifice of the chamber 6, and ranging vertically in parallelism as to each pair. The dovetail guides 8 terminate at their lower ends above and between transverse shoulders 9 extending at right angles to the plane of the guides 8; the walls of the chamber 6 beneath the shoulders 9, and laterally of each lateral opening of said chamber, being formed into spaced inclined faces 10, at the respective sides of each lateral orifice 8^b of the chamber 6, each of said pairs of faces 10 merging at its lower edge portion into similar spaced inclined faces 11, the inclination of which is, as is that of the faces 10, toward the longitudinal axis of the stem A, 9^b the inclination of the faces 11 being extremely in excess of that of the faces 10. The faces 11 merge into the projecting working member B, which is provided with a shank 12 extending upwardly within the chamber 6 and centrally subdividing the same in a plane transverse of the chamber 6 and parallel with those of the guides 8. The chamber 6 is therefore divided into two parts, as clearly shown, vertically of each of which parts extends a pair of the dovetail guides 8; and each of the bits a is provided with a shank 13 having dovetail tongues 14 fitting the dovetail guides 8 to hold said shank in position for movement within the chamber 6, confined by the respective pair of guides 8.

Each bit a is formed with a working head 15 at the lower end of the shank 13, the same being provided at its top with lateral plane faces 16 fitting the shoulders 9 upon the stem or body, and with inclined lateral or

inner faces 17 fitting the inclined faces 10 upon the stem or body. The main portion of the shank 13 fits the respective opening between the respective guides 8, being ⁵ projected near the upper end with an inclined shoulder 13^a. The lower outer edge portion 18 of the head 15 constitutes the cutting edge of the bit. Each bit shank 13 is pinned at its upper end, as at 19, to the lower end of a separate link arm 20 which is ¹⁰ accommodated in the respective channel 7, the said link arms extending upwardly and connected at their upper ends with a collar 21 ¹⁵ slidable upon the stem A, above the tapering portion 7^a, a coil spring 22 being disposed between the tapering portion 7^a and the collar 21, and normally holding the bits in elevated and laterally projected positions, or ²⁰ working positions, with the faces 16 of the bits in engagement with the shoulders 9 upon the stem A. The projecting working member B, beneath the shank 12, which as shown is disposed between the bits *a* which are slidably mounted at either side of the ²⁵ shank, is formed and organized in any preferred manner, as for connection with a string of boring or cutting tools, for developing the well boring or cutting beneath the under-reamer. A connection head 23 is ³⁰ shown beneath the shank 12, but any device or working part, or any means for suspending and holding any device or working part, beneath the stem A, falls within the spirit of the invention. The upper end of the ³⁵ shank 12 is integrally or firmly connected with the stem A at the upper portion of the chamber 6, and downwardly tapering blocks 24 are pinned to the upper end of the shank 12, at the upper portion of the ⁴⁰ chamber 6, as at 25, against which blocks the upper ends of the shanks 13 bear at their inner faces. These blocks 24 serve to hold the upper ends of the shanks with the tongues 14 bearing against the guides 8, ⁴⁵ when the bits are in elevated and working positions, as shown in Fig. 1.

The operation, method of use and advantages of the improved under-reamers constituting the invention will be readily understood from the foregoing description taken in connection with the accompanying drawing and the following statement:—The general type of apparatus under treatment being well understood with respect to its ⁵⁰ operation, it is only necessary to remark in general that before introduction of the under-reamer within the well casing the bits *a* are forced downwardly and inwardly from the working positions of the same shown in ⁵⁵ the drawing, against the tension of the spring 22 of the tension means C, until the faces 17 have passed beneath the inclined faces 10 upon the stem, and the heads 15 of the bits are brought into engagement with the shank 12 of the member B and with the ⁶⁰ edges at the tops of the lateral or inner faces 17 in engagement with the sharply inclined faces 11 upon the stem. The bits are then in retracted positions. The upper ends of the shanks 13 are permitted to swing upon the pinned connections 19 with the link arms 20, as the bit heads 15 are brought inwardly toward the shank 12 over the sharply inclined faces 11, such swinging action taking place when the upper ends of the shanks 13 have reached the inwardly tapering lower ends of the blocks 24. The bits thus swing upon axes at their upper ends, and this swinging action is most responsive to the conditions obtaining when the ascent of the under-reamer is begun. When the bits swing upon axes at their lower ends, drillings become pocketed between them and the stem, preventing unfailing and complete retraction. The swinging at the upper ends ⁷⁵ obviates all possibility of any jamming of the bits beneath the casing, and the blocking of the bits by drillings or any other foreign substance is entirely prevented. When the under-reamer is lowered to such ⁸⁰ position in the casing that the bits *a* have passed beneath the shoe of the casing, the bits are freed and permitted to move outwardly and upwardly, under the tension of the spring 22, into the positions shown in ⁸⁵ the drawing, with the faces 16 of the bits in engagement with the shoulders 9 upon the stem, and the faces 17 of the bits in engagement with the inclined faces 10 upon the stem. The cutting edges 18 are now ⁹⁰ in positions for service, and the under-reamer is operated in the usual manner through the stem A and the string above it. In the retraction of the bits the more sharply inclined faces 11 facilitate the final ⁹⁵ retractive movement, and also provide a useful degree of opposition to the tendency of the spring 22 to project the bits. At the same time, the projecting working member B, organized as may be desired, with a ¹⁰⁰ cutting tool or boring tool or the like, is utilized to perform its service beneath the bits of the under-reamer, so that the cutting or boring may be developed at the same time that the under-reaming operation takes ¹⁰⁵ place.

When the under-reamer is to be withdrawn from its position beneath the casing, it is elevated in the usual manner, and the shoulders 13^a upon the bits *a* contact with the shoe on the casing, causing the bits to be lowered and the heads of the same to be moved inwardly in the manner above described, so that the bits may traverse the casing in retracted inoperative positions, until the upper end of the casing is reached, when the bits again assume the normal projected positions shown in the drawing. ¹¹⁰

I do not desire to be understood as limiting myself to the particular provision, con- ¹¹⁵ 120 125 130

struction, formation, relative arrangement and combination of parts, members and features shown and described; but reserve the right to vary the same, in adapting the improvements to varying conditions of use, without departing from the spirit of the invention and the terms of the following claims:—

Having thus described my invention, I claim and desire to secure by Letters Patent:—

1. An underreamer comprising a body provided at its lower end with a chamber and with a downwardly projecting tool-carrying shank extending vertically throughout said chamber, said body having opposed faces each of which comprises an upper portion slightly inclined toward the shank and a lower portion increasingly inclined toward the shank, and bits mounted to traverse the respective opposed faces each with an inner face in contact therewith; said bits having shanks disposed in said chamber; and means pivotally suspending the bits at the upper ends of the shanks.

2. An underreamer comprising a body provided at its lower end with a chamber, said body being provided at the lower end of said chamber with two sets of faces at each side, each of said sets of faces having relatively inclined upper and lower portions, bits mounted within said chamber to move pivotally therein and being confined in said chamber to such movement, said bits co-acting each with two sets of said relatively inclined faces at one side of said chamber, means pivotally suspending the bits for movement within the chamber, and a tool-carrying shank spanning the chamber and ranging throughout the same vertically be-

tween the two sets of inclined faces and the co-acting bit at one side of the chamber and the corresponding sets of inclined faces and bit at the other side of the chamber; the means of pivotal suspension of said bits being at the respective sides of the upper end of said shank and clear thereof.

3. An underreamer comprising a body provided at its lower end with a chamber, said body being provided at the lower end of said chamber with two sets of faces at each side, each of said sets of faces having relatively inclined upper and lower portions, bits mounted within said chamber to move pivotally therein and being confined in said chamber to such movement, said bits co-acting each with two sets of said relatively inclined faces at one side of said chamber, means pivotally suspending the bits for movement within the chamber, and a tool-carrying shank spanning the chamber and ranging throughout the same vertically between the two sets of inclined faces and the co-acting bit at one side of the chamber and the corresponding sets of inclined faces and bit at the other side of the chamber; the means of pivotal suspension of said bits being at the respective sides of the upper end of said shank and clear thereof; and downwardly tapering blocks disposed at the respective sides of the upper end of the shank and with which the bits contact at their upper ends.

In testimony whereof, I have signed my name to this specification in the presence of two subscribing witnesses.

WILLIAM W. WILSON.
